United States Patent

Des. 236,041
Patented July 29, 1975

236,041

PROTECTIVE HELMET

Robert E. Conroy, Park Ridge, Ill., assignor to
Servotronics, Inc., Buffalo, N.Y.

Filed June 29, 1973, Ser. No. 374,963

Term of patent 14 years

Int. Cl. D2—03

U.S. Cl. D2—232

Fig. 2.

Fig. 1.

Fig. 4.

Fig. 3.

Fig. 6.

Fig. 5.

FIG. 1 is a front elevational view of a protective helmet, showing my new design;

FIG. 2 is a side elevational view thereof;

FIG. 3 is an opposite side elevational view thereof;

FIG. 4 is a rear elevational view thereof;

FIG. 5 is a top plan view thereof; and

FIG. 6 is a bottom plan view thereof.

I claim:

The ornamental design for a protective helmet, substantially as shown.
